EARTH WORKING IMPLEMENT

Carl F. Doerfler, Bend, Oreg.

Application March 1, 1948, Serial No. 12,241

2 Claims. (Cl. 37—168)

1 This invention relates generally to vehicles and particularly to an earth working implement.

The main object of this invention is to provide a single machine by means of which leveling, grading, terracing and border building may be accomplished at a minimum cost and with a relatively small amount of labor and time and at the same time performing the work in a neat and accurate manner.

The second object is to provide a machine of the class described which can be converted for use in different types of operations without the use of special tools or requiring extra man power for the change.

The third object is to provide a machine which will perform the operations mentioned without the use of additional equipment or guess-work.

The fourth object is to make the device self-leveling and to make it possible to set the machine to produce a pre-determined transverse slope to the roadway or hold the same level and to maintain this transverse position automatically with any type of prime mover.

I accomplish these and other objects in the manner set forth in the following specification, as illustrated in the accompanying drawings, in which:

Fig. 1 is a shortened side elevation of the device.
Fig. 2 is a plan of the device.

Fig. 3 is a rear end elevation showing the wheels on transversely level ground with the cutting blade set for level cutting.

Fig. 4 is similar to Fig. 3 but showing the supporting wheels on a hillside with the blade set to reduce the grade.

Fig. 5 is a vertical section taken along the line 5—5 in Fig. 1.

Fig. 6 is a vertical section taken along the line 6—6 in Fig. 1.

Like numbers of reference refer to the same or similar parts throughout the several views.

Referring in detail to the drawings, there is shown a vehicle whose ground engaging wheels 10 are mounted upon the oppositely turned crank ends 11 and 12 formed on the opposite ends of the axle 13 which is rockable in the bearings 14 secured on the sides 15, which are joined into an A frame by the ties 16 to 19 and the tubular head 20 from which depend the forks 21 between which is mounted the tongue 22 whose rear end is joined by the pin 23 to the lugs 24 which are welded to the members 15 and 20.

The leading end of the tongue 22 is connected by a pin 25 to a draw bar 26 which can be positioned on the draw bar plate 27 by means of a

pin 28 which passes through the holes 29 in the plate 27.

The holes 29 are formed in an arc whose center is a pin (not shown) which connects the members 26 and 27.

On top of the head 20 is secured a gooseneck 30 between which and the tongue 22 is connected a hydraulic jack 30—A to which fluid is admitted from a pressure source mounted on the tractor.

10 By this arrangement the elevation of the head 20 is easily controlled.

On the rear end of the side members 15 are the upright A frames 31 and 32 across the upper ends of which is mounted a shaft 33 from which 15 is suspended a heavy weight 34 by means of the braced arms 35, one of which is secured to the shaft 33 by means of the set screw 36.

On the shaft 33 is secured a crank arm 37 which is connected to a rod 38 in which is placed 20 a turn buckle 39. The lower end of the rod 38 is attached to a crank arm 40 which is secured on the axle 13.

It can be seen that since the weight 34 hangs 25 vertically at all times, it tends to rotate the shaft in a direction which will compensate for changes in the transverse slope of the ground upon which the wheels 10 travel.

Between the wheels 10 and the head 20 are the 30 flanged sections 41 which are joined by the gusset plates 42 and 43, through which extends a tubular housing 44 which is welded to the plates 42 and 43. Bearing bushings 45 receive the vertical pin 46 whose head 47 is welded to the top 35 plate 48 of the scraper blade 49 having the usual cutting blade 50 attached thereto.

In the flanges 51 of the sections 41 are formed the holes 52 which can be brought into register with the holes 53 in the plate 48 and the bulldozer blade 49 held in a fixed relation to the 40 length of the unit, by the pins 54.

It can be seen from the foregoing that since the 45 position of the turn buckle 39 determines the setting of the cranks 11 and 12 which control the transverse level of the members 15 and the attached blade 49, then any change in the transverse level of the roadway will, through the weight 34, produce a correcting tilt of the blade 49.

50 The depth of the cut is determined by the jack 30—A and the lateral movement of the dirt is controlled by the angular setting of the blade 49.

This construction makes it possible to use the device satisfactorily for any of the purposes set 55 forth in the statement of the invention.

I claim:

1. An implement of the class described, including an elongated frame having a pulling hitch at one end, an axle at the rearward end of said frame, said axle having oppositely turned eccentric wheel spindles at its ends, a ground engaging wheel on each spindle, a crank arm on said axle whereby a limited rocking motion may be imparted to said axle, a pendulum arm on said frame, an adjustable connection between said crank arm and said pendulum arm, a scraper blade supported by said frame and means for controlling the elevation of the pulling hitch.

2. An implement of the class described consisting of an elongated frame having a pulling hitch at one end, a scraper blade mounted between its ends, a pair of ground engaging wheels at the other end of said frame, said wheels having oppositely turned eccentric spindles on a common shaft capable of limited rocking movement, a pendulum suspended on said frame and adjustable connections between said pendulum and axle whereby said blade will be caused to slope in a relation opposite to the transverse slope of said wheels.

CARL F. DOERFLER.
